Primary Examiner — Sheryl Lane*Assistant Examiner* — Samantha Wood(74) *Attorney, Agent, or Firm* — Stephen J. Weyer, Esq.;
Stites & Harbison, PLLC(57) **CLAIM**

The ornamental design for a parking meter, as shown and described.

DESCRIPTION

FIG. 1 is a perspective view taken from the front, left side and top of a parking meter of our present design.

FIG. 2 is a front elevation view of the parking meter.

FIG. 3 is a rear elevation view of the parking meter.

FIG. 4 is a left elevation view of the parking meter.

FIG. 5 is a right elevation view of the parking meter.

FIG. 6 is a top plan view of the parking meter; and,

FIG. 7 is a bottom plan view of the parking meter.

The broken line showing the parking meter is included for the purpose of illustrating the environmental structure and forms no part of the claimed design.
